(21) Appl. No.: **29/209,389**

The ornamental design for a light source, as shown and described.

(22) Filed: **Jul. 15, 2004**

DESCRIPTION

Jan. 16, 2004 (JP) 2004-000913

FIG. 1 is a top perspective view of a light source of the present invention;

(51) LOC (8) Cl. **26-04**

FIG. 2 is a top view thereof;

(52) U.S. Cl. **D26/1**

FIG. 3 is a bottom view thereof;

(58) Field of Search D26/1-4; D10/114;

362/157, 158, 171-174, 183-208

FIG. 4 is a front view thereof;

(56) **References Cited**

FIG. 5 is a rear view thereof;

U.S. PATENT DOCUMENTS

FIG. 6 is a first side view thereof; and,

D250,819 S * 1/1979 Schindler et al. D26/1
D251,091 S * 2/1979 Schindler et al. D26/1
D464,744 S * 10/2002 Kato et al. D26/1

FIG. 7 is a second side view thereof.

FOREIGN PATENT DOCUMENTS

The ornamental design which is claimed is shown in solid lines in the drawings. Any broken lines in the drawings are for illustrative purposes only and form no part of the claimed design.
